CHARLES A. SCHLITTER, OF AVALON, AND MILO T. SCHOLL, OF PITTSBURGH, PENNSYLVANIA, ASSIGNORS, BY MESNE ASSIGNMENTS, TO FLEXOMET CORPORATION, OF PITTSBURGH, PENNSYLVANIA, A CORPORATION OF PENNSYLVANIA.

ROD PACKING.

Application filed May 10, 1922. Serial No. 559,866.

To all whom it may concern:

Be it known that we, CHARLES A. SCHLITTER and MILO T. SCHOLL, citizens of the United States, residing at Avalon and Pittsburgh, respectively, in the county of Allegheny and State of Pennsylvania, have invented new and useful Improvements in Rod Packings, of which the following is a specification.

10 Our invention relates to packings for piston-rods, valve-stems and the like, and its object is to provide composite packing-rings which will ensure fluid-tight joints under all conditions. This and other objects will be 15 made clear in the following description of our invention.

Referring to the accompanying drawing, Fig. 1 is a central longitudinal section of a stuffing-box embodying our invention, the 20 rod 2 being in side elevation; Fig. 2, a plan view of one of our improved packing rings; and Fig. 3, perspective view of a modified form of our packing ring. Fig. 4 is a development of a portion of a modified form 25 of our invention showing the metal ring with diagonal slots.

On the drawing, 1 designates a stuffing-box casing containing the reciprocable rod 2, surrounded by the packing rings 3, the 30 gland 4, and the cap 5, the latter being threaded to screw on the casing. The bottom of the casing preferably fits the rod 2 closely. Above this closely-fitting portion of the stuffing-box casing is an annular 35 chamber 6 having its bottom wall preferably tapered downwardly toward the rod 2 to form a shoulder or seat 7 for the lowest packing ring 3. Preferably a plurality of packing rings are superimposed on the seat 40 7 in the chamber 6, on the uppermost of which rings is seated the resilient gland or follower 4, preferably having its inner or lower end beveled upwardly and toward the rod 2. The inner face of the cap 5 engages 45 the top of the gland and, as it is screwed down, causes the gland to compress the packing-rings in the chamber 6, which is bounded by the inner wall of the stuffing-box, the rod, the shoulder or seat 7 and the gland.

50 The packing-rings are composite and are each composed preferably of a ring 8 of graphited asbestos having its inner wall

seated in an outwardly-facing annular channel in a metal ring 9 which bears directly on the rod 2. Each ring is divided or cut 55 entirely across diagonally at least at one place as shown at 10 in Figs. 1 and 3. Before assembling the rings 8 and 9, the flanges 12 of the ring 9 are preferably at right angles to the intermediate portion 13 thereof. 60 The divided flexible ring 8 can be easily inserted in the channel formed by the flanges 12 and the portion 13. The assembled rings 8 and 9, of which the ring 8 may be made of material square in cross-section, is placed 65 in a press having its opposing pressing faces constructed to depress the flanges 12 into the sides of the ring 8, in order that the flanges may form with the portion 13 a locking groove to retain the rings in their assembly. We have shown the ring 8 having 70 substantially a rectangular cross-section, but its periphery may be narrowed or widened with good results. The flanges 12 may occupy greater or smaller portions of the 75 ring 9 than shown.

The inner or annular portion 13 of the ring 9 has an annular groove 14 facing the rod 2 and lying centrally of the portion 13. The ring 9 may be composed of any suitable 80 flexible anti-friction metallic packing material preferably pressed from a sheet-like strip and bent into the shape shown and described. The groove 14 may be packed with lubricant. It also tends to trap water 85 of condensation, if any steam escapes along the rod 2, thereby forming a seal. The ring 9 may have a number of holes 15 extending entirely through the portion 13 along the groove 14. These holes permit any oil or 90 grease, with which the ring 8 may be impregnated, to pass into the groove and lubricate the rod 2. In case the ring 9 is made of rather hard metal the holes will somewhat weaken the portion 13 and allow it to 95 be narrowed more easily under the pressure of the gland.

The screwing down of the cap 5 causes the gland 4 to compress the rings 3 between its beveled face 16 and the beveled seat 7. 100 The pressure is first applied to the rings 8 which tend to spread so as to fill up adjacent vacant spaces and force the rings 9 in close contact with the rod 2. Eventually pressure

from the gland applied to the rings 9 in directions parallel with the rod 2 will narrow the portions 13 and make the grooves 14 narrower and somewhat deeper. The 5 groove 14 by reason of the uniform thickness of its wall causes the portion 13 to take a simple bend without liability of any wrinkles appearing at either side of the groove when a ring is compressed. If the 10 portions 13 were all parallel with the rod 2, it might yield irregularly as it narrows so as to form channels for the escape of fluid at the surface of the rod. The groove by 15 reason of the uniform thickness of its wall ensures that the rings will maintain a seal with the rod 2. When the rings 9 arranged as in Fig. 1 are compressed sufficiently by the gland 4 the wall of the groove bulges outwardly and compresses the packing ring 20 8, and the annular portions of the rings at each side of the groove will move relatively one toward the other without disturbing or 25 breaking their line contacts with the rods.

In Fig. 3, I show a packing ring with the 25 joint 10 extending entirely across one side of the same; and also with the joint 11 extending through the ring 9 only, though it might extend through the ring 8 also, if desired. The number of joints 10 and 11 may 30 be as many as desired.

The gland 4 is shown composed of a helical spring 17 having one end seated in the gland-cap 18. The rings 8 are preferably made of fibrous asbestos coated with graphite, but they may be composed of other substances, as rope and the like.

On Fig. 4, I show the metal ring 9^a provided with diagonal slots 15^a in place of the round holes shown in Fig. 3. Preferably the 40 slots have their adjacent ends terminating at about a transverse line across the ring. The slots permit a better distribution of the metal during the crushing or narrowing of the ring due to the action of the gland 4.

We claim:—

1. A packing-ring comprising an annular metallic channel member of flexible metal having substantially uniform thickness adapted to contact with a movable rod embraced thereby, the channel member being open peripherally, and a ring of yielding packing seated in the channel, the base of the channel member bulging outwardly to form an annular wave whereby, when the ring is compressed, it bulges outwardly in a uniform manner and compresses the packing.

2. A packing-ring comprising an annular metallic channel member of flexible metal having substantially uniform thickness, 60 adapted to contact with a movable rod embraced thereby, the channel member being open peripherally, and a ring of yielding packing seated in the channel, the base of the channel member bulging outwardly to 65 form an annular wave of curved cross-section whereby, when the ring is compressed, it bulges outwardly in a uniform manner and compresses the packing.

3. A packing-ring comprising an annular metallic channel member of flexible metal having substantially uniform thickness adapted to contact with a movable rod embraced thereby, the channel member being open peripherally, and a ring of yielding 75 packing seated in the channel, the base of the channel member bulging outwardly to form an annular wave and the portions of the base at each side of the said wave bulging inwardly to form annular waves whereby, when the ring is compressed, its base bulges outwardly in a uniform manner and compresses the packing, and the portions at 80 each side of the base bulge inwardly.

Signed at Pittsburgh, Pennsylvania, this 85
8th day of May, 1922.

CHARLES A. SCHLITTER.
MILO T. SCHOLL.
